BALL CHECK VALVE

Domer Scaramucci, 3245 S. Hattie, Oklahoma City, Okla.

Filed Sept. 18, 1964, Ser. No. 81,789

Term of patent 14 years

(Cl. D91—3)

FIG. 1

FIG. 2

FIG. 3

FIG. 4

FIG. 5

FIG. 1 is a perspective view of a ball check valve looking at one end and one side of the valve.

FIG. 2 is an end view of the valve looking at the end opposite the end shown in FIG. 1.

FIG. 3 is a side view of the valve looking at the side not shown in FIG. 1.

FIG. 4 is a bottom view of the valve.

FIG. 5 is a top view of the valve.

I claim:

The ornamental design for a ball check valve, as shown.
